UNITED STATES PATENT OFFICE.

OLIVER N. ECKBURG, OF AMBOY, ILLINOIS, ASSIGNOR OF ONE-HALF TO RALPH FANELLI, OF AMBOY, ILLINOIS.

GARMENT-SACKING APPARATUS.

Application filed March 6, 1928. Serial No. 259,585.

This invention relates to store furniture and more particularly to a sacking apparatus by means of which protecting sacks or envelopes may be applied to suits and other 5 garments in order to protect them from dust while waiting to be delivered.

At the present time it is customary for a tailor or cleaner to place a suit or coat upon a hanger after it has been repaired or cleaned 10 and cover it with a large sack or envelope open at its lower end and having its upper end formed with an opening through which a supporting hook of the hanger extends so that the hook may be engaged with a rail or 15 bar and the garment suspended beneath the bar until called for or delivered to a customer. The sacks or bags employed for this purpose and especially those used upon over-coats are of such length that they cannot be 20 easily set in place about the garment and, therefore, one object of the invention is to provide an apparatus by means of which the sacks may be suspended in an elevated position and then moved downwardly into position 25 about a garment suspended beneath the open lower end of the sack.

Another object of the invention is to guide movement of the sack while moving into and out of position to envelop a garment and 30 also to cause the hook of a garment hanger to be guided outwardly through the small opening in the top of the sack so that the hook may be easily grasped in order to remove the garment after the sack is in place and transfer it to the supporting rail from 35 which it is suspended until delivered to the customer.

Another object of the invention is to provide the apparatus with sack holders so connected with each other that when one carrying a sack is moved downwardly into position to dispose the sack about a garment suspended beneath it the other sack holder will be moved upwardly to draw another sack upwardly into position to have a suit or other garment disposed beneath it in position for sacking and thereby allow a number of garments to have protecting sacks quickly applied to them.

Another object of the invention is to allow the device to be employed together with a supporting standard or the standard omitted and a cross bar carried by the standard secured to a ceiling or other overhead support.

Another object of the invention is to per-

mit the standard to be vertically adjusted so that it may be conveniently operated and to provide the standard with means for carrying a supply of sacks so that they may be conveniently reached when the apparatus is 60 in use.

The invention is illustrated in the accompanying drawings, wherein

Figure 1 is a view showing the improved sacking apparatus in front elevation, a sack 65 carried by one of the sack holders being indicated by dotted lines;

Fig. 2 is a side elevation of the improved sacking apparatus;

Fig. 3 is a fragmentary view showing a 70 portion of the standard partially in section and partially in elevation;

Fig. 4 is a transverse sectional view through the standard taken on the line 4—4 of Fig. 1, and

Fig. 5 is a view in elevation illustrating a modified form of sacking apparatus.

The improved sacking apparatus includes a standard having a tubular lower portion 1 which projects upwardly from a base 2 80 formed with fastener receiving openings 3 so that it may be firmly secured upon a floor or other support. The upper standard section 4, which is preferably a solid bar although it may consist of a tube, is slidably received in the hollow lower standard section 1 so that it may be vertically adjusted and a set screw 5 is provided so that the upper standard section may be securely but releasably held in a set position. A collar 6 fits 90 loosely about the upper standard section and rests upon the upper end of the lower standard section. This collar which may be provided with a set screw to retain it stationary, if so desired, carries arms 7 which project 95 radially from the collar and are intended to carry a supply of sacks. By this arrangement the supply of sacks will be conveniently located where they may be quickly reached by the operator of the apparatus.

At its upper end the standard section 4 is threaded into a socket 8 carried by a cross bar or head 9. This cross bar projects horizontally from opposite sides of the standard and from its upper edge projects a flange 10 105 having sockets 11 adjacent its ends. Arms 12 which depend from the flange 10 have their upper ends screwed into the sockets 11 and at their lower ends the arms are provided with hooks 13 for engagement by the usual hooks 110

provided upon coat hangers of a conventional construction. The arms are of such length that the hooks at their lower ends will project downwardly beneath garment-enveloping sacks and, therefore, when a sack of the greatest length is disposed about one of the arms and drawn upwardly the hook of a garment hanger may be readily engaged with the hook at the lower end of the arm.

10 In order to engage the sacks and move them upwardly and downwardly into and out of position to envelop garments suspended upon the arms, there has been provided clamps 14 which are slideable longitudinally upon the arms. These clamps are of a duplicate construction and each includes jaws 15 which are disposed at opposite sides of its cooperating arm and connected by handles 16 between which the arm extends, as shown in Fig. 2. Springs 17 are employed to yieldably retain the jaws closed, and it will be readily seen that, when the handles are pressed toward each other, the jaws will be opened so that a sack may be moved upwardly upon the lower end portion of an arm with the arm extending through the opening in the top of the sack and portions of the sack at opposite sides of the arm gripped by the jaws. Flexible strands 18 which may be light chains or strong cords extend across the crosshead and have their end portions threaded through eyes 19 carried by the arms adjacent their upper ends and their end portions are extended downwardly and secured in openings or eyes formed in the upper ends of the handles 16. It will thus be seen that the two clamps will be so connected to each other that, when one is moved downwardly along its arm, the other will be drawn upwardly. Pull chains 20 are provided so that the clamps may be easily drawn downwardly from an elevated position. The structure shown in Fig. 5 is identical with that shown in Figs. 1 and 2, except that the standard is omitted and the crosshead is secured to beams of a ceiling or other suitable overhead support by screws or equivalent fasteners 21.

When the apparatus is in use, the crosshead may be secured to a ceiling or other overhead support or if the standard is employed the set screw 5 may be released and after the upper standard section has been vertically adjusted to dispose the crosshead at the desired height the set screw again tightened.

50 A supply of sacks are placed upon the arms 7 and are removed one at a time, care being taken to select a sack of the proper length according to whether a short garment, such as a suit, or a long garment, such as an overcoat, is to be covered. After a sack has been engaged with a clamp adjacent the lower end of its cooperating arm the other clamp is drawn downwardly through the medium of its pull chain 20, thereby drawing the first clamp and the sack carried thereby upwardly.

When the sack is in the elevated position, the hook at the lower end of the arm extends downwardly below the sack and, therefore, the hook of a garment hanger may be easily engaged with the hook of the arm. It should be noted that the arm extends longitudinally through the sack thereby retaining the sack in its proper position and guiding longitudinal movement thereof. After the garment has been suspended beneath the elevated sack, another sack is removed from one of the arms 7 and engaged with the clamp which has been drawn downwardly. The pull chain of the first clamp is then grasped and drawn upon. This causes the first clamp and the sack carried thereby to be moved downwardly and the second clamp and the sack carried thereby to be drawn upwardly. As the sack moves downwardly, it will be disposed about the garment suspended from the arm in enveloping relation thereto and when the clamp has been drawn downwardly as far as possible and its handle moved to open the jaws the sack will drop into proper position about the garment with the hook of the garment hanger projecting upwardly through the opening in the top of the sack. The garment can then be easily lifted from the lower end of the arm from which it is suspended and transferred to a hanger bar or other frame from which it will be suspended until called for or delivered to a customer. It will thus be seen that a sack may be easily and quickly applied to a garment and that, while one sack is moved downwardly into place about a garment, another will be drawn upwardly into position to have a garment suspended beneath it.

Having thus described the invention, I claim:

1. A garment sacking device comprising vertically disposed guides having their lower ends adapted to be engaged by garment hangers, sack carriers slideable longitudinally of said guides, and means connecting said carriers to effect upward movement of one while the other is moving downwardly whereby a sack may be drawn upwardly into position for use while another is lowered into enveloping relation to a garment suspended beneath the cooperating guide.

2. A garment sacking device comprising independent sack holders adapted to engage sacks open at their lower ends and support the same, means whereby garments may be supported below the sack holders, and means to simultaneously effect upward movement of one sack holder and downward movement of the other sack holder whereby a sack may be moved into position for use while another is lowered into enveloping relation to a garment.

3. A garment sacking device comprising vertically disposed guides having their lower ends adapted to be engaged by garment hang-

ers, sack carriers slidable longitudinally of said guides, and flexible elements connecting said sack carriers whereby when one is drawn downwardly to dispose a sack in enveloping

5 relation to a garment supported beneath the cooperating guide and another sack carried by the other sack carrier moved upwardly into position for use.

4. A garment sacking device comprising 10 vertically disposed guides having their lower ends adapted to be engaged by garment hangers, sack holders disposed about said guides and slidable vertically thereon and each provided with sack engaging means at opposite 15 sides of its cooperating guide, and means to simultaneously effect upward movement of one sack holder and downward movement of the other sack holder whereby a sack may be moved into position for use while another 20 is lowered into enveloping relation to a garment.

5. A garment sacking device comprising vertically disposed guides having their lower ends adapted to be engaged by garment hangers, sack holders disposed about said guides and slidable vertically thereon and each provided with sack engaging means at opposite sides of its cooperating guide, eyes adjacent the upper ends of said guides, and flexible 30 members passed through said eyes and engaged with said sack holders whereby when one is drawn downwardly to dispose a sack in enveloping relation to a garment supported beneath the cooperating guide and another 35 sack carried by the other sack carrier moved upwardly into position for use.

6. A garment sacking device comprising 40 an overhead support, arms depending therefrom in spaced relation to each other and adapted to have garment hangers suspended from their lower ends, sack holders slidable longitudinally upon said arms, and means connecting said sack holders to effect simultaneous movement of the sack holders in opposite directions.

7. A garment sacking device comprising 45 an overhead support, arms depending therefrom in spaced relation to each other and adapted to have garment hangers suspended from their lower ends, sack holders fitting loosely upon said arms and slidable vertically thereon, the sack holders having sack engaging jaws at opposite sides of their respective cooperating arms, and means connecting said sack holders to effect simultaneous movement of the sack holders in opposite directions.

8. A garment sacking device comprising 50 an overhead support, arms depending therefrom in spaced relation to each other and adapted to have garment hangers suspended from their lower ends, sack holders fitting loosely upon said arms and slidable vertically thereon, the sack holders having sack engaging jaws at opposite sides of their respective

cooperating arms, guides adjacent the upper ends of said arms, and flexible means passed through said guides and secured to said sack holders whereby one sack holder will be drawn upwardly while the other is moved 70 downwardly.

9. A garment sacking device comprising 75 an overhead support, arms depending therefrom in spaced relation to each other and adapted to have garment hangers suspended from their lower ends, sack holders fitting loosely upon said arms and slidable vertically thereon, the sack holders each having sack engaging jaws at opposite sides of its co-operating arm and actuating handles at opposite sides of the arm connecting the jaws to simultaneously actuate the same, guides adjacent the upper ends of said arms, and flexible members slidably engaged with said guides and having their end portions extended downwardly and secured to the handles of 80 said sack holders.

10. A garment sacking device comprising 90 an overhead support, arms depending therefrom in spaced relation to each other and adapted to have garment hangers suspended from their lower ends, sack holders fitting loosely upon said arms and slidable vertically thereon, the sack holders each having sack engaging jaws at opposite sides of its co-operating arm and actuating handles at opposite sides of the arm connecting the jaws to simultaneously actuate the same, means yieldably retaining the jaws closed, guides carried by said arms, flexible members slidably engaged with said guides and having their ends secured to the handles of said jaws, and means carried by said jaws and depending therefrom to facilitate drawing the same 95 downwardly.

11. A garment sacking device comprising a standard to rest upon a floor, a crosshead carried by said standard, arms depending from said crosshead, sack holders slidable vertically upon said arms, the lower ends of said 100 arms being adapted to have garment hangers suspended therefrom, and means connecting said sack holders to effect simultaneous movement thereof in opposite directions.

12. A garment sacking device comprising a standard having a lower section to rest upon the floor and an upper section slidable vertically into and out of the lower section, means to releasably secure the upper section in a set position, a crosshead carried by the upper section, arms depending from said crosshead and having their lower ends adapted to be engaged by garment hangers, sack holders slidably vertically upon said arms and connected to effect simultaneous movement thereof in opposite directions, and means to hold a supply of sacks carried by said standard.

13. A garment sacking device comprising 115 a standard having a lower section to rest upon the floor and an upper section slidable 120

vertically into and out of the lower section, means to releasably secure the upper section in a set position, a crosshead carried by the upper section, arms depending from said 5 crosshead and having their lower ends adapted to be engaged by garment hangers, sack holders slideable vertically upon said arms and connected to effect simultaneous movement thereof in opposite directions upon the arms.

14. A garment sacking device comprising a standard to rest upon a floor, a crosshead carried by said standard and provided with a horizontal flange, arms depending from the 10 end portions of said flange and having their

lower ends adapted to be engaged by garment hangers, and sack holders slideable vertically upon said arms and connected to effect simultaneous movement thereof in opposite directions upon the arms. 20

15. A sacking device comprising independent sack holders adapted to engage open-ended sacks, means whereby articles to be 25 sacked may be supported in operative relation to the open ends of the sacks, and means to effect movement of the sack holders in opposite directions whereby one sack may be moved into position for use while another is 30 moved into enveloping relation to an article.

In testimony whereof I affix my signature.

OLIVER N. ECKBURG. [L. s.]
